UNITED STATES PATENT OFFICE.

ALEXANDER ERWIN HODGES, OF TECUMSEH, OKLAHOMA TERRITORY.

WASHING-MACHINE.

SPECIFICATION forming part of Letters Patent No. 599,181, dated February 15, 1898.

Application filed May 15, 1897. Serial No. 636,681. (No model.)

To all whom it may concern:

Be it known that I, ALEXANDER ERWIN HODGES, of Tecumseh, in the county of Potawatomie and Territory of Oklahoma, have 5 invented a new and Improved Washing-Machine, of which the following is a full, clear, and exact description.

The object of the improvement is to provide a new and improved washing-machine, 10 which is simple and durable in construction, easily manipulated, and arranged to insure a proper rubbing and washing of the clothes in a very short time.

The invention consists principally of a receptacle mounted to rock, a rubbing-cylinder within the said receptacle, a frame in which the cylinder is journaled, and an arm loosely connected with the said frame and adapted to receive a swinging motion from the said 20 receptacle to move the rubbing-cylinder in an opposite direction to the movement of the receptacle.

The invention also consists of certain parts and details and combinations of the same, as 25 will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement. Fig. 2 is a sectional side elevation of the same on the line 2 2 of Fig. 3, and Fig. 3 is a transverse section of the same on the line 35 3 3 of Fig. 2.

The improved washing-machine is mounted on a suitably-constructed main frame A, in which are journaled the trunnions B, secured to the sides of a semicircular receptacle C, free to swing in the frame A and provided on its inner surface with laterally-extending bars C' to form a rubbing-board on the bottom of the receptacle. Within the receptacle C and operating in conjunction with the rubbing-board is a rubbing cylinder or roll D, journaled at its ends in a frame E, formed on its sides with vertically-disposed guideways E', loosely engaged by the lower ends of arms F, extending upwardly in the receptacle 45 through the fixed and loose cover parts C² C³ thereof and then bent downwardly on the outside of the receptacle to form the arms F', con-

nected with each other below the receptacle by a transverse rod F². The arms F' extend loosely through the keepers, carrying the 55 trunnions B, as shown in Fig. 3. On the rod F² and near the ends thereof are secured the cords or ropes G G', of which the rope G extends from the rod F² to the left to then pass over a pulley H and then extend to the right along 60 the under side of the receptacle C to connect at the right-hand side thereof with an eye I, attached to the receptacle. The other rope G' extends from the rod F² to the right, to then pass over a pulley H' and to then extend 65 along the under side of the receptacle C to the left-hand side thereof to connect with an eye I'. The pulleys H and H' are journaled in suitable bearings in the frame A, it being understood that two sets of ropes 70 and pulleys are preferably used, as indicated in Figs. 2 and 3.

The receptacle C is provided with a suitable handle J for conveniently rocking the receptacle during the washing operation. Locking devices K are arranged on the frame A and receptacle C to lock the latter in position while placing the clothes into the receptacle or removing the clothes therefrom.

Now it will be seen that when the clothes 80 are in the receptacle and the latter is unlocked the operator by moving the handle J downward causes the receptacle C to swing in the direction of the arrow a'. The receptacle in doing so exerts by the ropes G a pull 85 on the rod F² to swing the latter in the inverse direction of the arrow a', so that the arms F move the frame E, and consequently the rubbing-cylinder D, in a like direction, the rubbing-cylinder being free, however, to 90 move up and down with its frame E, owing to the loose connection of the frame with the arms F. When the receptacle C is swung in the opposite direction, then the rod G' pulls on the rod F² to swing the arms F' F to the 95 right, so as to again move the frame E and the rubbing-cylinder D in the inverse direction of the movement of the receptacle C.

Now it will be seen that by the arrangement described a proper rubbing of the clothes in 100 the receptacle C takes place without danger of tearing the clothes, as the rubbing-cylinder D is free to revolve in its frame and is free to move up and down in the receptacle, owing

to the loose connection of the frame with the arms F.

Having thus fully described my invention, I claim as new and desire to secure by Letters 5 Patent—

1. A washing-machine, comprising a receptacle mounted to rock, a rubbing-cylinder within the said receptacle, a frame in which the cylinder is journaled, guideways in the 10 said frame, arms loosely engaging the said guideways, and means substantially as described, for imparting a swinging motion to the said arms in an opposite direction to the swinging motion of the receptacle, the said 15 means comprising two sets of ropes and pulleys, which ropes are connected with a bar attached to the said arms and pass over the pulleys to then fasten to opposite sides of the receptacle, substantially as shown and described.

2. The combination with a support, of an oscillatory receptacle mounted thereon, a roll

mounted within the receptacle, an arm movably mounted on the receptacle and having connection with the roll, and a flexible connection attached to the arm and to the receptacle and running over a portion of the support. 25

3. The combination with a support, of an oscillatory receptacle mounted thereon, a roll 30 contained within the receptacle, a frame in which the roll is carried, an arm movably mounted on the receptacle and having connection with the frame, and two flexible connections attached to the arm and run oppositely from the arm, the flexible connections being also attached to the receptacle, and the flexible connections being run over a portion of the support. 35

ALEXANDER ERWIN HODGES.
